Patented Sept. 1, 1964

199,038

LANTERN

Thomas H. Nicholl, Leawood, Kans., and Donald Cartner, Kansas City, Mo., assignors to Nicholl Brothers, Inc., Kansas City, Mo., a corporation of Missouri

Filed July 1, 1963, Ser. No. 75,588

Term of patent 14 years

(Cl. D48—24)

Fig. 1.

Fig. 2.

Fig. 3.

Fig. 4.

Fig. 5.

FIG. 1 is a perspective view of a lantern embodying our design.

FIG. 2 is a side elevational view thereof, the opposite side being a mirror image of the side shown.

FIG. 3 is a rear elevational view thereof.

FIG. 4 is a front elevational view thereof and showing the convex lens.

FIG. 5 is a plan view thereof.

The bottom of the lantern is plain.

We claim:

The ornamental design for a lantern, as shown and described.
